UNITED STATES PATENT OFFICE

ALBERT N. CRAMER, OF TOLEDO, OHIO, ASSIGNOR TO OWENS-ILLINOIS GLASS COMPANY, OF TOLEDO, OHIO, A CORPORATION OF OHIO

GLASSWARE ANNEALING LEER

Application filed May 28, 1928. Serial No. 281,254.

The present invention relates to improvements in glassware annealing leers, particularly to that type in which ware is transported through a leer tunnel upon a continuously moving conveyor.

An object of the present invention is to provide in a glassware annealing leer an improved ware conveyor construction which is unusually effective in maintaining ware in an upright position during its passage through the leer tunnel.

Another object is to provide a ware conveyor which will not interfere materially or to an objectionable extent, with free circulation of an annealing medium therethrough. To this end, the conveyor comprises a series of interconnected metal strips set on edge and bent in a fashion to permit hinging the strips together. The separable connection between the bent metal strips or conveyor sections is such that the strips may be easily removed from the unit singly or in groups when necessary. This ware conveyor, because of its peculiar construction, successfully resists narrowing under the strain of operating conditions and thereby further contributes to improved annealing conditions and economy in leer maintenance.

A further object is to provide a novel conveyor supporting means peculiarly adaptable for cooperation with a conveyor of the character above referred to. To this end, the supporting means comprises an open grate bar structure offering little interference to the upward circulation of an annealing medium therethrough and at the same time supporting the upper reach of the ware conveyor in a manner to insure uniform wear of the conveyor transversely of the latter. Further this conveyor supporting means is such that the upper reach of the conveyor is maintained in a true horizontal plane and thereby insures carrying of the ware through the leer in an upright position.

Because of the intense heat to which certain portions of the leer elements are subjected and the difference in coefficients of expansion of metals, warping of sections of the conveyor supporting means in the usual leer is often experienced. This is mainly due to

failure to provide means whereby one portion of the leer is free to expand a greater degree than another portion subjected to the same temperature. Accordingly, the present conveyor support is built up of separate sections individually removable so that any warped or otherwise distorted section or sections may be readily removed and replaced without great difficulty and at a minimum cost. Further, the sections are so relatively arranged that they may expand independently of each other and of adjacent elements to thereby additionally provide for elimination of warping.

A still further object is to provide a novel type of conveyor roll peculiarly and well adapted for use with a conveyor of the type referred to above. To this end, each roll includes a series of bars extending transversely relative to the conveyor and spaced from each other to contact with alternate transversely extending sections of the conveyor, said bars and conveyor sections having relatively wide flat bearing surfaces, whereby exceptionally effective frictional driving engagement between the rolls and conveyor is obtained.

In leer operation wherein an endless conveyor carries ware through the leer tunnel, it is quite advantageous to bring the temperature of the conveyor to a degree approximating that of the ware to be deposited thereon prior to placing the ware in the leer to prevent the conveyor from drawing heat from the ware and causing additional strains in the latter. The present invention contemplates preheating the ware conveyor by embodying in one of the conveyor rolls at the front end of the leer, suitable burners which direct sufficient heat into contact with adjacent portions of the conveyor to raise the temperature of the latter to a degree substantially corresponding to that of ware placed in the leer.

Often-times blasts of intense heat discharge from the front end of the leer into the faces of the persons feeding the leer, such condition quite obviously being dangerous and extremely objectionable. To overcome this objection, the present invention contemplates the provision of exhaust flues in the usual gate or

door at the front end of the leer whereby these blasts of intense heat are caused to move upwardly through the flues to the atmosphere, instead of forwardly beneath the gate or door as is customary.

It is also an object of the present invention to construct a glassware annealing leer in which gas burners or the like heating devices are spaced along the leer tunnel and positioned directly below the ware support so as to direct the heating gases upward through said open spaces in said support and between the articles being annealed. Said open spaces prevent unnecessary interference by the supporting elements with free circulation of the annealing or heating medium. Also, the burners are decreased in number and spaced further apart in a progressive fashion from the heating zone to the cooling zone to thereby improve annealing conditions. This application of heat is in direct contrast to the method employed in the usual open fired leer wherein the heat is conducted through a series of flues and directed downwardly upon the ware. Considerable loss in heat is experienced in the latter method.

Other objects will be apparent hereinafter. In the accompanying drawings:

Fig. 1 is a vertical central longitudinal section of a portion of a leer constructed in accordance with the present invention.

Fig. 2 is a plan view with parts broken away to disclose the ware conveyor and its supporting means, as well as their relation to the burners.

Fig. 3 is a front end elevation of the leer with parts broken away to show the conveyor rolls and the gate construction.

Fig. 8—A is a detail perspective view showing one of the dampers for the leer door.

Fig. 4 is a fragmentary detail perspective view showing the construction of ware conveyor supporting means.

Fig. 5 is a fragmentary detail perspective view showing the ware conveyor structure.

Fig. 6 is a fragmentary detail sectional view illustrating the driving engagement between the conveyor and the conveyor rolls.

Fig. 6—A is a detail sectional view of the conveyor roll construction and its relation to the conveyor sections.

Fig. 7 is a detail sectional view illustrating the heating means embodied in one of the conveyor rolls for preheating the ware conveyor.

Fig. 8 is a transverse sectional view taken substantially at the line VIII—VIII of Fig. 7.

Fig. 9 is a detail sectional elevation of the fuel injector.

In the drawings, the leer is illustrated as comprising a floor 15 supported on pillars 16, or the like members, and including side walls 17 and a leer roof or ceiling 18. The floor, side walls and roof may be formed of any

suitable insulating material and are held in assembled relation by a framework 19 (Figs. 1 and 2). Longitudinally extending channel iron units 20 are supported upon the upper side of the floor 15, and are interconnected at their ends by transverse channel iron units 21 (Fig. 1). The longitudinal units are formed with transversely aligned openings 22 through which suitable burner pipes 23 extend, said pipes having burner tips 24 projecting upwardly therefrom to direct heat into the heating chamber of the leer. These channel iron units, together with the floor 15 and conveyor support, form a combustion chamber in which the combustion of fuel sets up a pressure acting to prevent eddy or convection currents from carrying cold air into contact with the ware.

At the front end of the leer, the burner pipes 23 are positioned quite close to each other and the burner tips 24 are quite numerous. The spaced relation between the pipes 23 increases toward the rear end of the heating and preliminary cooling areas, and the burner tips are decreased in number so that ware passing through the leer is subjected to steadily decreasing degrees of heat during movement through a predetermined length of the leer.

The floor of the tunnel (Figs. 1, 2 and 4) through which the ware is carried rests upon the longitudinal side members 20 in spaced relation to the series of burners which are supported in said side members. This floor includes a plurality of longitudinally spaced cross bars 25 which are preferably T-shaped in cross section and each comprising a centrally arranged flange 30 rising vertically from the base portion to support grate bar units 31 making up the conveyor supporting area. These cross bars are uniformly spaced apart distances corresponding to the lengths of the grate bar units 31 which are arranged in transverse rows across the leer and are individually removable.

Each grate bar unit includes a flat rectangular body portion 32 (Fig. 4). An arm 33 extends laterally from one side of the body portion 32 and is formed at its outer end with an angular finger 35 which rests upon a flange 30 of one of the cross bars 25. This arm 33 is preferably increased in transverse width in proximity to its connection to the body portion 32 whereby its conveyor supporting area is increased. A pair of laterally extending arms 34 is formed on the opposite side of the body portion 32, said arms diverging outwardly and terminating in angular fingers 35 which rest upon the vertical flange of one of the cross bars 25 as shown in Fig. 4. These arms 33 and 34 are for the greater part relatively narrow transversely but of considerable height whereby they are quite capable of supporting the ware conveyor and load carried thereby, yet will

offer little interference to the free upward circulation of an annealing medium through the tunnel floor and conveyor for contact with the ware.

- 5 In assembling these grate bars units, the directions in which the single arms 33 of adjacent units extend is reversed so that the angular fingers 35 are uniformly spaced apart along the cross bars 25 whereby in the 10 assembling of the next succeeding transverse row of cross bars, the fingers at the rear ends of said next succeeding row may be supported upon the cross bars in the spaces between the forward fingers of the preceding row. By 15 this arrangement, the grate bar units may be removed independently of each other for replacement or for other reasons.

The fingers 35 (Fig. 4) are spaced a short distance from the vertical webs 30 so that 20 the grate bars may expand independently of each other and the remaining structure. Thus, varying of the conveyor support is reduced to a minimum, and, consequently, the conveyor may at all times occupy a true horizontal plane to properly support bottles or the like thereon.

The upper surfaces of the body portion, arms and fingers of the grate bar units 31 are in the same horizontal plane, thereby insuring 30 maintenance of the ware conveyor in a horizontal plane during its travel through the leer. Thus, there is little likelihood of ware upsetting during its passage through the leer. By arranging the arms 34 of the grate bar 35 units diagonally relative to the direction of travel of the conveyor (Figs. 2 and 4), the wearing of the lower face of the conveyor is uniform throughout. This latter feature obviously serves to maintain the ware supporting 40 surface of the conveyor in a true horizontal plane.

The unit at the forward end of the leer floor (Figs. 1 and 4) comprises a cross bar 26 supported on the transverse channel iron unit 45 21 and formed with a relatively wide conveyor supporting plate 27 arranged in a horizontal plane with the conveyor supporting surfaces of the other leer floor units. A transverse row of arms 28 formed on the cross bar 26 50 terminate in angular fingers 29 resting upon the cross bar 25 in the spaces between the fingers at the rear ends of the first row of grate bar units 31.

From the foregoing, it is seen that the tunnel floor construction is such that it will effectively support the ware carrying reach of the conveyor in a true horizontal plane to insure supporting the ware in an upright position at all times, and is of such construction 55 that it will readily carry the conveyor with a capacity load, and at the same time offer a minimum interference to the free circulation of the annealing medium upwardly into and through the leer tunnel.

60 65 The ware conveyor 131 (Fig. 5) embodies

certain principles employed in the grate bar construction, whereby maximum strength is obtained with minimum resistance to circulation of the annealing medium for contact with ware supported on the conveyor. Also, 70 Monel metal is preferred in constructing the conveyor, since this metal quickly absorbs and dissipates heat. Thus, the conveyor quickly heats up at the front end of the leer prior to receiving the ware, and cools rapidly at the 75 other end of the leer so that parts of the conveyor may be readily removed if necessary. The conveyor 131 is composed of a longitudinal series of transverse sections 40 hinged together, each section comprising a metal strip 80 set on edge and bent into a series of substantially U-shape sections 41, adjacent sections opening in opposite directions longitudinally of the conveyor. These transverse sections 40 are separably connected by removable hinge 85 rods 42 (Fig. 5) extending through transversely aligned openings 43 in said elements. The opposite ends 44 of the hinge rods are passed through openings 45 in the end portions of the strips and bent upon themselves 90 to prevent accidental displacement.

This conveyor 131, which, as just stated, consists of a series of these peculiarly formed strips set on edge, travels over the tunnel floor in conveying ware through the leer, 95 and due to the open formation of both the conveyor and floor, the annealing medium may freely circulate through both the floor and conveyor for contact with ware supported on the latter. Since the conveyor units comprise 100 strips of metal of uniform width bent as described and set upon the grate bars, it is evident that the ware supporting reach of the conveyor will be maintained in a horizontal plane and thereby support the articles in 105 an upright position while being annealed. If circumstances require removal or replacement of portions of the conveyor, it is only necessary to remove two of the transverse hinge rods 42 at the desired points. In this manner, the conveyor may be lengthened or 110 shortened or sections replaced if desirable.

The ware conveyor 131 is of the endless type and runs over a pair of superposed conveyor rolls 50 at the front end of the leer and has its lower reach 51 supported on transverse rollers 52 below the floor 15 of the leer. A driving roll 50 (Fig. 6) is provided at the rear end of the leer. The lower reach of the conveyor runs outside of the leer and is exposed to view of the operator who may readily determine when sections should be replaced. Further, the location of the lower reach of the conveyor outside of the leer insures sufficient cooling thereof to permit removal or replacement of sections without difficulty.

The conveyor rolls 50 at the opposite ends of the leer are constructed to insure proper engagement with the leer or ware conveyor 130

131 heretofore described. Each roll (Figs. 1, 3, 6 and 6^a) comprises a transverse shaft 55 journalled in transversely aligned bearings 56 in the side walls 17 of the leer and 6 carrying a series of longitudinally spaced disks 57 about whose peripheries are arranged a plurality of bars 58. These bars extend longitudinally of the shaft 55 and are spaced apart circumferentially on the disks. Each 10 bar 58 is rectangular in cross section and is set into a series of aligned notches 59 in the disks 57 and held in these notches or seats by screws 60 or like fasteners. In mounting the bars 58 on the disks to form the conveyor 15 rolls, said bars are spaced apart distances approximating that between the hinge rods 42 which interconnect the conveyor sections 40. Thus, when the conveyor passes over the rolls at opposite ends of the leer, the flat inner 20 faces of alternate conveyor sections will frictionally engage the outer broad flat faces of two adjacent bars 58, the intermediate unit and connector rods being positioned between said two adjacent bars 58. Thus, provision 25 is made for obtaining maximum frictional driving engagement between the driving roll 50 at the delivery end of the leer (Fig. 6) and the ware or leer conveyor 131.

Provision is made for preheating of the 30 ware conveyor 131 in advance of placing ware thereon at the front end of the leer. The means for effecting this preheating consists of a chamber 65 (Fig. 1) through which the lower reach of the conveyor travels. This 35 chamber houses the two vertically spaced conveyor rolls and a pair of transverse burner pipes 66, the latter having burners 66^a thereon for directing flames against those portions of the conveyor immediately above 40 the burners. In addition to this heating means, one of the conveyor rolls, preferably the lower one (Figs. 1 and 7), is equipped with heating devices. These devices (Figs. 45 7, 8 and 9) consist of a plurality of burners 67 arranged in staggered relation along the hollow shaft 55, the latter serving as a manifold for supplying fuel to the burners. One 50 end of this manifold (Fig. 7) is tapered to form a Venturi tube 68 terminating in a yoke 69 having a bearing 70 axially aligned with the Venturi tube 68. A spud 71 is axially adjustable in a sleeve 72 which in turn is journalled in said bearing 70, said spud (Fig. 9) 55 71 formed at its inner end with an adjusting nut 73 which is rotatively connected to a fuel supply pipe 74, the latter being capable of movement in the direction of its length when the spud is adjusted as will be apparent. 60 By loosening a set screw 75 in the sleeve 72 and rotating the nut 73, the spud 71 may be adjusted axially relative to the inlet of the Venturi tube 68 to thereby vary the size of the air gap 76 and obtain the desired mixture 65 of air and gas for introduction into the manifold. This set screw 75 also separably

connects the sleeve 72 and a collar 72^a, the latter holding the sleeve in the bearing 70. The spud and sleeve remain stationary with the fuel supply pipe 74 while the yoke 69 rotates with the shaft 55, the pipe 74 being 70 supported by any suitable means (not shown). The flames projected from the burners 67 effectively heat the entire conveyor roll 50 (Figs. 1 and 2) and the ware or leer conveyer to a degree approximating 75 that of the ware being placed on the conveyor. Thus, the tendency for the conveyor to draw heat from the bottom of the ware is minimized if not entirely eliminated, so that strains and stresses are not unduly set 80 up in the ware being annealed.

Ware to be annealed is sometimes placed in the receiving end of the leer automatically by mechanical ware handling devices, although it is the practice in many plants to 85 feed the leer by hand. This latter practice means that the operators must, with the aid of suitable implements, set the ware upright on the ware conveyor in the leer and in doing so, closely approach the open end of the 90 tunnel. With the ordinary leer, a gate at the ware receiving end of the leer is adjusted to provide an opening through which the ware may be placed in the annealing chamber, and through this opening blasts of intense heat 95 are frequently blown into the faces of the operators.

According to the present invention (Figs. 1, 3 and 3A), the gate 80 is of rectangular shape and of hollow construction. Portions 100 of the lower and inner walls of the gate are cut away to form exhaust openings 81 providing communication between the annealing chamber and vertical flues 82 which project downwardly into the hollow gate through 105 openings 83 in the upper wall 84 of the gate. These flues or outlet pipes 82 are suspended from a cross bar 85 (Fig. 3) which is fixed to the upper ends of standards 85^a and supports the gate elevating mechanism 86 which 110 may, as shown, be of ordinary construction including a pair of threaded rods 87 extending upwardly through said cross bar and carrying bevel gears 88 running in mesh with bevel gears 89 on a transverse shaft 90. This 115 shaft 90 is journalled in suitable bearings 91 on the upper side of the cross bar 85 and carries a manually operable hand wheel 92 at one end which may be rotated to change the elevation of the gate 80. The rate of 120 movement of heat exhausted through the flues 82 is controlled by dampers 93 or valves which are adjustable across the upper ends of said flues.

A leer embodying the features set forth 125 herein provides for economy in annealing in that the cost of maintenance is relatively low. Obviously, this is in part due to the fact that the elements most seriously affected by the intense heat are readily removable 130

and replaceable without necessitating a general dis-assembly of the leer. Further, the means for preheating the ware conveyor contributes materially to economical operation and improved annealing, as pointed out above.

Modifications may be resorted to within the spirit and scope of the appended claims.

What I claim is:

- 10 1. A ware conveyor supporting floor for glassware annealing leers, comprising a series of cross bars arranged in parallel relation to each other, and substantially Y-shaped grate bar units arranged in rows parallel with and between pairs of cross bars and having their end portions supported on the latter, said units formed to provide a perforate support assembled.
- 15 2. A grate bar unit comprising a body portion, a pair of divergent arms extending laterally from one side of the body, a single lateral arm extending from the other side of said body, and members at the ends of said arms for engagement with a support.
- 20 3. A grate bar unit comprising a body portion, a pair of divergent arms extending laterally from one side of the body, a single lateral arm extending from the other side of said body, and angular fingers at the ends of said arms adapted to engage a support, the upper surfaces of the body, arms and fingers being arranged in the same plane.
- 25 4. In a glassware annealing leer, a ware conveyor comprising a plurality of transversely extending pivotally connected elements, each element comprising a flat metal strip bent to sit on edge upon a conveyor support.
- 30 5. In a glassware annealing leer, the combination of an annealing chamber, a ware conveyor running through said chamber and comprising a series of pivotally connected transverse elements, each element comprising a sheet metal strip set on edge and bent into a series of U-shaped sections whereby a perforate conveyor is formed.
- 35 6. In a glassware annealing leer, an endless ware conveyor, a perforate conveyor roll over which the conveyor is trained, and means associated with the roll to apply heat to those portions of the conveyor passing over said roll.
- 40 7. In a glassware annealing leer, an endless ware conveyor, a perforate roll at the front end of the leer, and means arranged in part within the roll to heat the latter and thereby preheat the ware conveyor.
- 45 8. A conveyor roll comprising an elongated hollow shaft forming a manifold, burners radiating from said manifold, means to inject fuel into the manifold, and means carried by the manifold for engagement with a ware conveyor or the like.
- 50 9. In a glassware annealing leer, an endless ware conveyor, a conveyor roll over

which the conveyor runs, said roll comprising an elongated hollow shaft forming a manifold, burners radiating from said manifold, means to inject fuel into the manifold, means carried by the manifold for engagement with said ware conveyor, the last named means comprising radial circular flanges on the manifold, and a series of circumferentially spaced bars fixed to the flanges and extending longitudinally of the manifold.

10. In a glassware annealing leer, an endless ware conveyor, a conveyor roll over which the conveyor runs, said roll comprising an elongated hollow shaft forming a manifold, burners radiating from said manifold, means to inject fuel into the manifold, means carried by the manifold for engagement with said ware conveyor said fuel injecting means including a non-rotating spud axially aligned with the manifold, and means to axially adjust said spud to control the mixture of fuel.

11. In a glassware annealing leer, a ware conveyor comprising a plurality of transversely extending pivotally connected elements, each element comprising a flat strip of metal bent to sit on edge upon a conveyor support.

Signed at Toledo, in the county of Lucas and State of Ohio, this 25th day of May, 1928.
